(57) **CLAIM**

The ornamental design for a child's indoor sleeping tent, as shown and described.

DESCRIPTION

FIG. 1 is a front perspective view of a child's indoor sleeping tent according to the present invention.

FIG. 2 is a front elevation view of the child's indoor sleeping tent illustrated in FIG. 1.

FIG. 3 is a rear elevation view of the child's indoor sleeping tent illustrated in FIG. 1.

FIG. 4 is a left elevation view of the child's indoor sleeping tent illustrated in FIG. 1.

FIG. 5 is a right elevation view of the child's indoor sleeping tent illustrated in FIG. 1.

FIG. 6 is a top plan view of the child's indoor sleeping tent illustrated in FIG. 1.

FIG. 7 is a bottom plan view of the child's indoor sleeping tent illustrated in FIG. 1; and,

FIG. 8 is a lower perspective view of the child's indoor sleeping tent illustrated in FIG. 1.

The broken lines depict portions of the child's indoor sleeping tent that form no part of the claimed design.

1 Claim, 8 Drawing Sheets
